UNITED STATES PATENT OFFICE.

WILLIAM E. BROWN, OF SACRAMENTO, CALIFORNIA.

CUSPIDOR COVER.

Application filed September 11, 1925. Serial No. 55,781.

This invention relates to cuspidors and more particularly to a sanitary cover or protector for the mouth thereof.

The object of the invention is to provide a cover which may be readily applied to the funnel-shaped mouth of a cuspidor and which not only forms a sanitary protector therefor but also presents an adhesive surface which will trap flies alighting thereon and thus prevent the spread of disease.

Another object of the invention is to so construct the cover that the blank from which it is made may be firmly but releaseably held in engagement with the funnel-shaped mouth of the cuspidor.

A further object of the invention is to so coat the upper surface of the blank that the marginal portions thereof will be prevented from sticking to an adjacent blank when several of said blanks are nested for storage or shipment while at the same time permitting the blanks to be readily detached for use when desired.

This invention is illustrated in the accompanying drawing, wherein

Figure 1 is a view showing a cuspidor of a conventional construction partially in side elevation and partially in section with the improved cover applied thereto;

Fig. 2 is a top plan view of the blank from which the cover is formed, and

Fig. 3 is a fragmentary sectional view taken on the line 3—3 of Fig. 2.

The cuspidor to which the cover has been shown applied is of conventional construction and includes a bowl 1 having the usual funnel-shaped mouth 2. When a cuspidor of this type is in use, spittle has a tendency to accumulate upon the upper inclined surface of the funnel-shaped mouth instead of flowing into the bowl and when flies alight thereon they often carry germs and spread disease. This is one of the causes for the spread of tuberculosis and other similar diseases, and it is to prevent this spreading of disease germs by flies that the improved cover has been devised.

The cover is preferably formed from a paper blank shaped as shown in Fig. 2, but any other suitable flexible material may be employed capable of having its end portions readily moved into overlapping relation to each other. The blank is segmental in shape and constitutes the major portion of a circle but the entire blank is not intended to be used when forming the cover. Referring

to Figs. 2 and 3, it will be seen that the marginal portion 3 of the blank has been offset from the body portion 4 by a line of depressions 5 which are pushed through from the upper face of the blank. The blank is scored in this manner in preference to a series of slits or other perforations as it is desired to prevent the coating of the blank which will be hereinafter referred to from leaking through when a number of blanks are stacked one upon another. The marginal portion 3 between the scored line 5 and periphery of the blank is coated with rosin so that when the blank is placed in face to face contact with another blank the marginal portions will not stick together and, therefore, the blanks may be readily separated by first separating the marginal portions and pulling them apart. The portion of the upper face which is enclosed by the scored line is coated with a sticky substance of a water-proof nature and serves to ensnare flies which light upon it.

Since it is water-proof any spittle deposited upon the cover will readily flow downwardly and pass into the bowl of the cuspidor. The formula preferably employed in compounding the sticky substance consists of forty parts of rosin dissolved in sixty parts of boiling cotton seed oil or one pound of rosin dissolved in five pounds of hot twenty-eight degree mineral oil and four ounces of castor oil. If desired a poison may be added so that the flies will be more quickly killed and their death insured if in any way they should succeed in escaping after alighting upon the sticky substance. It is further desired to prevent the sticky substance from penetrating the paper from which the blank is formed and causing it to be sticky on both sides and, therefore, the paper from which the blanks are stamped will be oil-proof by impregnating the paper in a rubber solution, such as one ounce of washed dried Pará rubber completely dissolved in one gallon of benzine to which is added one ounce of carbon bisulphide mixed with sulphur chloride in the ratio of 16:1. The cuspidor cover is primarily intended to prevent the spread of tuberculosis and, therefore, before the paper is coated with the sticky substance the well-known tuberculosis symbol may be printed upon its upper face or a suitable legend, such as shown in Figs. 1 and 2, inscribed thereon to call attention to the fact that a person

should be careful to spit into the cuspidor.

When the cover is in use, the marginal edge portion 3 is separated from the main body of the blank by tearing along the scored line 5 and the end portions of the blank moved into overlapping relation to each other to form a cover of an inverted frustro-conical shape. When so shaped, the cover will rest in flat contact upon the upper face of the funnel mouth 2 of the cuspidor, as shown in Fig. 1. In order to retain the cover in place upon the mouthpiece, there has been provided tongues 6 which are anchored to the under face of the cover and extend radially thereof with their free end portions extended beyond the inner periphery of the cover and adapted to be bent into engagement with the inner face of the cuspidor bowl. When so positioned, the tongues serve to very effectively hold the cover in place but permit of it being readily removed when it is desired to clean the cuspidor and replace the cover with a new one. Before the cover is in use, the tongues may extend radially from the inner periphery of the blank or may be folded back upon themselves beneath the body portion of the blank, as indicated by dotted lines in Fig. 2. These tongues may be formed of any material desired but it is preferred to employ a strip 7 of thin sheet metal which may be easily bent and enclose the sheet metal

strip in a paper sleeve or casing 8 which constitutes a guard for the sheet metal and prevents danger of cutting the fingers when bending it and also permits the tongue to be glued to the under face of the blank. 35

Having thus described the invention, I claim:

A sanitary cover for cuspidors comprising an arcuate strip of flexible material having its ends spaced from each other, a continuous line of depressions extending entirely about said strip in spaced relation to the marginal edges thereof and defining a border adapted to be torn from the body of the strip along the line of depressions, a coating of sticky substance upon the upper face of said body within the confines of the said line of depressions, a resinous coating upon the upper face of said border, the ends of said body being overlapped after said border has been removed and secured by the sticky coating to form a concavo-convexed cover adapted to fit snugly in a flared mouth piece of a cuspidor, and fasteners carried by said body and projecting from the same and adapted to be bent into engagement with a portion of the cuspidor to retain the cover in place. 50

In testimony whereof I affix my signature. 55
